UNITED STATES PATENT OFFICE.

EDWARD A. JOHNSTON, OF STERLING, ILLINOIS, ASSIGNOR TO INTERNATIONAL HARVESTER COMPANY, A CORPORATION OF NEW JERSEY.

TONGUE-HITCH.

No. 831,514.

Specification of Letters Patent.

Patented Sept. 18, 1906.

Original application filed December 20, 1905, Serial No. 292,533. Divided and this application filed February 26, 1906. Serial No. 302,832.

To all whom it may concern:

Be it known that I, EDWARD A. JOHNSTON, a citizen of the United States, residing at Sterling, in the county of Whiteside and State of Illinois, have invented a new and useful Improvement in Tongue-Hitches, of which the following is a complete specification.

This is a divisional application of the one filed by me December 20, 1905, Serial No. 292,533, hay-loader. While the tongue-hitch which forms the subject-matter of the present application is particularly well adapted for use in connection with the hay-loader shown and described in the original application, it is also applicable to practically all types of two-wheel-supported hay-loaders.

The object of the invention is to provide an improved and simple device for engaging and disengaging a hay-loader from the rear end of the wagon. It is of importance in machines of this class to provide a construction which will enable them to be readily attached to and detached from the wagons of different height either when the load is on or when the wagon is empty and to so arrange the parts that the detachment can be effected either by the man on the wagon which is being loaded or from the ground without the necessity of getting beneath the wagon to effect the disconnection. In the present construction to protect the gathering-cylinder, which is placed in advance of the supporting-wheels, and avoid throwing the weight of the entire forward part of the loader on the cylinder when the loader is detached from the wagon a tongue-hitch having a folding leg is employed.

Referring to the accompanying drawings, Figure 1 represents a side elevation of a hay-loader embodying my invention. Fig. 2 is an enlarged detail view, in side elevation, of the tongue-hitch. Fig. 3 is a front elevation of same; and Figs. 4 and 5 represent detail sectional views taken, respectively, on the lines 4 4 and 5 5 of Fig. 2.

A stub-tongue 1 is secured to and extends forwardly from the cross-sill 2 of the main frame of the hay-loader, the forward end of said tongue being rigidly braced by means of the obliquely-arranged brace-rods 3 and 4. A supplemental tongue 5 is hinge-connected

to the stub-tongue 1 by means of the yoke-shaped iron 6, the pivotal axis 7 thereof lying a short distance in front of the rear end of the said stub-tongue. The supplemental tongue is provided with a hook 8 on its forward end, which is made to engage a suitable member 9 on the wagon with which it connects. A rearwardly-folding leg 10 is pivoted to the forward end of the stub-tongue 1, the stop 11 having formed at its upper end the hooks 11', which engage a forward projection 7' of the yoke 7, limiting the forward movement of the said leg 10 and yet permitting of rearward movement thereof.

In order to control the vertically-swinging movement of the supplemental tongue 5, the following means are employed: A clevis 12 is adjustably pivoted at its upper end to the supplemental tongue, the pivotal axis being formed by the bolt 13. Rock-arms 14 are fixed to the pin 14', which has a bearing in the stub-tongue 1, and these rock-arms are made to engage at their lower ends the lower ends of the side bars of the clevis 12, as shown in Fig. 4. It is evident that a rocking movement of the pin 14' and arms 14 will through the clevis 12 operate to lift the supplemental tongue 5. To effect this rocking movement, one of the rock-arms 14 has fixed thereto or preferably formed integral therewith a bent lever 15, this bent lever enabling the clevis 12 to be swung to a locked position with respect to the fulcrum of the arms 14, as shown by full lines in Figs. 1 and 2, thus locking together the stub-tongue 1 and supplemental tongue 5.

The relative position of the fulcrum and pivotal centers are indicated in Fig. 2 by *a*, *b*, and *c*, which represent, respectively, the fulcrum of the clevis 12 on the supplemental tongue, the fulcrum of the rock-arms 14 on the stub-tongue, and the pivotal connection between said rock-arms and clevis. *a'*, *b*, and *c'* represent the same centers after the bent lever 15 has been moved forwardly and the supplemental tongue raised to the position shown by dotted lines in Fig. 2. A coiled spring 16, reacting between the two tongues near the pivotal axis 7, exerts a pressure which tends to separate the two, such movement being prevented, however, by the arrangement of the clevis and bell-crank when

in a locked position, as shown in Figs. 1 and 2, but when tripped will cause the supplemental tongue to rise and disengage itself from the member 9 of the wagon-rack, as indicated by dotted lines in the latter figure. A rope 16' connects, through the link 17, with bent lever 15 and enables the locking mechanism to be tripped. The rope 16' extends to a position within convenient reach of an operator on the ground or may extend to a position within reach of an operator on the wagon. To attach the tongue-hitch to the wagon, the wagon is backed up in front of the hay-loader and the supplemental tongue 5 is pressed down and the bent lever 15 and rock-arms 14 moved forwardly, the several parts moving from the dotted-line position of Fig. 2 to the full-line position of the same figure, the hook 8 being thereby brought into engagement with the corresponding fastening on the member 9 of the wagon-rack. The link 17, connecting with the bent lever 15 in conjunction with the pin 18, permits of a greater latitude of movement of the said bent lever.

What I claim as my invention, and desire to secure by Letters Patent, is—

1. A tongue-hitch comprising a stub-tongue, a supplemental tongue having a pivotal connection at its rear end therewith, means for effecting a locking connection between the forward end of said supplemental tongue and the stub-tongue, and means for supporting the forward end of the stub-tongue when detached from the wagon-rack.

2. A tongue-hitch comprising a stub-tongue, a supplemental tongue having a pivotal connection at its rear end therewith, means for effecting a locking connection between the forward end of said supplemental tongue and stub-tongue, and a folding leg depending from the forward end of the stub-tongue.

3. In combination with a hay-loader, a tongue-hitch comprising a stub-tongue, a

supplemental tongue having a pivotal connection at its rear end therewith, means for effecting a locking connection between the forward end of said supplemental tongue and stub-tongue, a spring operating to move the two tongues apart, and means for supporting the forward end of the stub-tongue when detached from the wagon-rack.

4. In combination with a hay-loader, a tongue-hitch comprising a stub-tongue, a supplemental tongue lying above said stub-tongue and pivotally connected at its rear end thereto, a rack-engaging hook on the forward end of the supplemental tongue, rock-arms pivotally mounted upon said stub-tongue, a clevis pivoted to the supplemental tongue and connected with the lower ends of said rock-arms in such relation that the parts will be locked together when the rock-arms are moved to their forward position, means for controlling the position of the rock-arms, and a rearwardly-folding leg depending from the forward end of the stub-tongue.

5. In combination with a hay-loader, a tongue-hitch comprising a stub-tongue, a supplemental tongue lying above said stub-tongue and pivotally connected at its rear end thereto, rock-arms fulcrumed in the stub-tongue and depending on either side thereof, an upwardly-extending bent lever as one piece with said rock-arms, a link-and-rope connection with said bent lever, a clevis pivoted to the supplemental tongue and connected with the lower ends of said rock-arms in such relation that the parts will be locked together when the rock-arms are moved to their forward position, means for controlling the position of the rock-arms, and a rearwardly-swinging leg depending from the forward end of the stub-tongue.

EDWARD A. JOHNSTON.
